ALARM MECHANISM.

1,288,917.

Specification of Letters Patent. Patented Dec. 24, 1918.

Application filed January 5, 1917. Serial No. 140,823.

To all whom it may concern:

Be it known that I, DWIGHT F. KILGOUR, a citizen of the United States, and resident of Lexington, in the county of Middlesex 5 and Commonwealth of Massachusetts, have invented an Improvement in Alarm Mechanisms, of which the following description, in connection with the accompanying drawings, is a specification, like characters on the 10 drawings representing like parts.

This invention pertains to improvements in alarm mechanisms and more particularly, though not exclusively, to alarm mechanisms for use in connection with automatic 15 sprinkler systems.

Sprinkler systems are usually provided with some form of alarm means intended to give an alarm when a leak develops in the system, or when one or more of the sprinkler 20 heads releases the water because of fire or for any other reason. Such alarm mechanisms are usually actuated by the flow of the water through the system, or by variations in the pressure in the system.

Great annoyance has been caused by false alarms occasioned by the sounding of automatic alarms when the water in the pipes of the sprinkler system is reciprocated, or the pressure changed because of water hammer, or other changes in pressure or flow 30 not occasioned by leakage or release of a sprinkler head. It is among the objects of my invention to provide an alarm system which will not sound an alarm except when 35 a sprinkler head releases it or when a leak develops in the system, my improved system not sounding an alarm when the pressure in the sprinkler system is changed, or when water hammer occurs.

Referring to the drawings which show one illustrative embodiment of a preferred form of my invention:

Figure 1 is a side elevation of an automatic alarm controlling system interposed 45 in a sprinkler system and is illustrative of a preferred form of my invention;

Fig. 2 is a plan view of the controlling valve below the line 2-2 of Fig. 1;

Fig. 3 is a vertical sectional elevation of 50 the controlling valve on the line 3-3 of Fig. 2;

Fig. 4 is a horizontal sectional view of the controlling valve on the line 4-4 of Fig. 3; and

55 Fig. 5 is a vertical section on an enlarged

scale through a portion of the alarm controlling apparatus shown in Fig. 1.

Referring to the drawings and the preferred form of my invention, I have shown a pipe 5 adapted to supply water to the 60 alarm controlling valve and to the pipe 6, which connects with the distributing pipes throughout the building protected by the sprinkler system. Interposed between the pipe 5 and the pipe 6, I have shown an 65 illustrative alarm-controlling valve having a body portion 7 and provided with an oscillatory valve element 9 constituting one form of flow-actuated-controlling means and normally positioned adjacent the bottom 70 portion of the body portion 7, as shown in full lines in Fig. 3. In this position the valve element or vane 9 substantially closes connection between the supply pipe 5 and the discharge pipe 6. The illustrative valve 75 element 9 shown in the drawings is pivoted at 10 and provided with a stem 11 having a portion projecting outside the body of the valve. I preferably provide a manually operable lever 13 connected to the valve stem 80 11. Through the valve element 9 I preferably provide a relatively small aperture 64 which may, as shown, be provided with a check valve 65 adapted to permit discharge 85 of water through the aperture 14 from the supply pipe 5 to the discharge pipe 6, but which preferably prevents the return of any substantial amount of water from the discharge pipe 6 to the supply pipe 5. After 90 water is admitted to the whole sprinkler system, the valve element 9 is preferably located in its lowermost position, being held there by gravity. If any substantial amount of water escapes from the sprinkler system, the pressure on the upper side of the valve element 9 will be lowered and the pressure of the water in the supply pipe 5 will raise the valve element 9 to permit the free flow of water from the supply pipe 5 to the discharge pipe 6. As the valve element 9 is 100 raised, it rocks the valve stem 11, thereby raising the handle 13.

I preferably connect the alarm system or systems to the lever or handle 13. In the 105 illustrative embodiment of my invention disclosed in the drawings, I have shown electric wires 15 and 16, which may be connected to any suitable electric alarm. The circuit is preferably opened and closed by movement of the lever 13 and sufficient lost motion is 110

preferably provided to necessitate a considerable movement of the vane before the contact is made. In the illustrative embodiment of my invention disclosed in the drawings, a movable terminal connection 17 is connected to the wire 16 and to the lever 13, and a suitable stationary terminal connection 18 is connected to the wire 15 and to the body portion 7 of the valve.

10 I preferably provide coöperating water alarm means, which may take the form of any suitable water motor adapted to operate a suitable gong or other suitable device. I may control the admission of water to the 15 water alarm means by a supplementary valve 20, which is preferably of the plug cock type and which is preferably connected to the valve element 9 by the lever 13, connecting link 21 and supplementary valve 20 lever 22. The plug cock 20 is preferably so disposed that water cannot pass through it until considerable movement of the lever 13 has taken place. To provide for the 25 ready control of the water passing through the water motor, I may interpose a pressure actuated valve, best shown in Fig. 5, which may include the body portion 30 having a connection 31 with the supplementary valve 20, an inlet connection 32 connected to any 30 portion of the pressure system and outlet connection 33 connected to the water motor 19.

The valve body 30 preferably contains a piston valve which is preferably provided 35 with a large pressure area 34 adapted to be operated by water from the connection 31 and with balanced pistons 35 and 36 located one on each side of the inlet 32 when the valve is closed, but adapted to permit flow 40 of water from the inlet 32 and outlet 33 when the valve is open. The chamber 37 above the piston 34 is preferably provided with an escape outlet 38 to prevent accumulation of pressure in the chamber 37. The 45 pistons 34, 35 and 36 are preferably connected by a valve piston rod 39 which preferably, as shown, extends exteriorly of the valve casing 30 and may be provided with a handle 40 so that the valve may be closed 50 by hand.

If any considerable amount of air is 55 trapped in any of the pipes of the sprinkler system on the discharge side of the alarm apparatus, this air will have a tendency to expand and be contracted as the pressure in the water main is raised or lowered. This tends to produce a flow of water through the alarm valve when the pressure in the main is increased and the entrapped 60 air compressed. If the increase in pressure were rapid, sufficient flow of water would take place to operate the alarm. To prevent this, I preferably provide means for maintaining pressure in the sprinkler system, 65 even when the pressure in the main is

greatly reduced. This means preferably comprises a check valve 60 in the supply line to the alarm valve adapted to prevent flow of water from the sprinkler system to the water supply main. I preferably interpose 70 an air chamber 61 between the check valve 60 and the alarm valve, so that a maximum pressure will be maintained in the sprinkler system and alarm controlling mechanism, even when the pressure in the supply main is 75 lowered. The location of the relatively large air chamber on the supply side of the alarm controlling system also tends to absorb changes in pressure occasioned by water hammer and to reduce to a minimum the 80 fluctuation of the flow actuated alarm controlling element when water hammer occurs.

The operation of the valve is as follows: When the sprinkler system is filled with 85 water, the lever 13 is depressed either by hand or by its own weight, thereby positioning the valve element 9 in the lower portion of the casing 7. While the valve element 9 is in this position, if there is any 90 disturbance of pressure due to water hammer or other temporary unbalancing of water pressures, the valve element 9 may move a considerable distance back and forth against its seat without completing the 95 electric circuit between the wires 15 and 16, and without opening the plug cock 20. Should cumulative, unidirectional, infrequent unbalancings of pressure take place 100 tending to move the valve element 9 in an upward direction, it may seat itself between such unbalancings of pressure by reason of its weight and that of its connected lever, which preferably tends to close the valve. Should, however, any considerable amount 105 of water be withdrawn from the discharge pipe 6 because a sprinkler head has been released by fire or because of a leak in the system, the valve element 9 will be pushed to such position that a free flow of water 110 from the supply pipe 5 and the discharge pipe 6 is afforded. The space between the moving element 17 and the fixed element 18 is preferably such that a contact will be 115 made as soon as the valve element 9 is moved upwardly sufficiently to provide direct communication between the supply pipe 5 and the discharge pipe 6. Similarly, after this movement of the valve element 9 has taken 120 place, the cock 20 is preferably turned sufficiently by the lever 13, link 21 and supplementary valve lever 22, to permit the admission of water under the piston 34. Pressure between the pistons 35 and 36 being 125 balanced and one side of the piston 34 not being under pressure, the valve stem 39 with its connected piston will move longitudinally of the valve body 30, thereby moving the piston 35 past the outlet connection 33 and permitting free flow of water from the 130

inlet 32 to the outlet 33 and thence to the water alarm.

The alarm valve may be closed, either manually or automatically by the operation of gravity. To permit the exhaust of fluid from beneath the piston 34, I may provide a draw-off cock 41, which may be opened after the valve element 9 has been returned to its normal position in the bottom 10 of the valve body. After opening the cock 41, the valve stem 39 with its connected parts may be returned to their normal position by pressure on the handle 40. The lever 13 also provides a convenient means for testing the 15 alarm system.

While I have shown and described a preferred embodiment of my invention, it will be understood that changes involving omission, substitution, reversal and rearrangement of parts may be made without departing from the scope of my invention. My 20 invention is best defined by the following claims:

1. An automatic sprinkler alarm system 25 comprising, in combination, alarm means, an alarm-controlling valve, a water supply pipe for conducting water to said alarm-controlling valve, a water discharge pipe adapted to be maintained full of water un- 30 der pressure and extending from said alarm-controlling valve to the sprinkler heads, said alarm-controlling valve providing a flow-controlled element normally balanced by the water pressure on its opposite sides and hav- 35 ing provision for movement within definite limits of distance without affording direct communication between said supply pipe and said discharge pipe, and without initiating operation of said alarm means.

2. In an automatic sprinkler alarm valve, 40 a water supply pipe for conducting water to the valve, a water discharge pipe leading to the sprinkler heads and normally filled with water under pressure equal to the pressure 45 in said supply pipe, a flow-controlled element operatively interposed between said pipes and presenting equal areas to the water on opposite sides thereof, alarm means controlled by said flow-controlled element, and 50 a casing presenting lateral seats for said flow-controlled element through a substantial movement thereof, whereby said flow-controlled element may reciprocate through a substantial distance without opening direct 55 communication between said supply pipe and said discharge pipe and without initiating operation of said alarm means.

3. In an automatic sprinkler alarm controlling system; a water inlet connection 60 from the water supply; a water outlet connection to the sprinkler heads; a flow controlled element operatively interposed between said water inlet connection and said water outlet connection; alarm means; 65 and means providing for limited flow ac-

tuated movement of said flow controlled element while maintaining out of communication said inlet and outlet connections and without actuation of said alarm means but for actuation of said alarm means on 70 further flow actuated movement of said flow controlled element.

4. In an automatic sprinkler alarm controlling system, a water inlet connection from the water supply; a water outlet connection to the sprinkler heads; a pressure controlled element operatively interposed between said water inlet connection and said water outlet connection; alarm means; and means providing for limited pressure ac- 75 tuated movement of said pressure controlled element while maintaining out of communication said inlet and outlet connections and without actuation of said alarm means but for actuation of said alarm means on fur- 80 ther pressure actuated movement of said pressure controlled element.

5. In an automatic sprinkler alarm controlling system; alarm means; a water inlet connection; a water outlet connection; a flow 90 controlled element normally interposed between said inlet and outlet connections but permitting free passage of water from said inlet connection to said outlet connection when pressure in said outlet connection is 95 reduced, said flow controlled element and elements actuated thereby providing for limited movement without direct communication between said inlet and outlet connections and without alarm but providing for 100 alarm when direct communication is opened between said inlet and outlet connections.

6. In an automatic sprinkler alarm system a valve body; an inlet connection; an outlet connection; a flow controlled vane be- 105 tween said connections; and means providing for a limited flow of water from said inlet connection to said outlet connection without flow actuated movement of said vane, said means opposing such flow of water from 110 said outlet connection to said inlet connection.

7. In an automatic sprinkler alarm system a valve body; an inlet connection; an outlet connection; a flow controlled vane; a 115 pivot stem for said vane extending exteriorly of said valve body; a fixed electric contact terminal; and a movable electric contact terminal connected to said pivot stem, said terminals providing for limited rotation of 120 said pivot stem without alarm and for completing a circuit to initiate alarm on further rotation of said pivot.

8. In an automatic sprinkler alarm system a water alarm; a piston valve for admitting 125 and excluding water from said water alarm; a cock for admitting pressure to move said piston valve from closed to open position; and a flow controlled vane controlling opening of said cock,

9. In an automatic sprinkler system alarm-controlling means, a water supply conduit, a check valve distinct from said alarm controlling means in said conduit and an elastic pressure fluid reservoir connected to said conduit between said alarm-controlling means and said check valve.
10. In an automatic sprinkler alarm-controlling system the vane 9, the supply pipe 5, the discharge pipe 6, the valve body providing for limited movement of the vane 9 without direct communication between the supply pipe 5 and the discharge pipe 6, and alarm means operatively connected to the 15 vane 9.

Copies of this patent may be obtained for five cents each, by addressing the "Commissioner of Patents, Washington, D. C."

11. In an automatic sprinkler alarm-controlling system the vane 9, the supply pipe 5, the discharge pipe 6, the valve body providing for limited movement of the vane 9 without direct communication between the supply pipe 5 and the discharge pipe 6, and alarm means providing lost motion operatively connected to the vane 9.

12. In an automatic sprinkler system the check valve 60, the air chamber 61 and co-operating pressure - actuated-alarm-controlling means distinct from said check-valve.

In testimony whereof, I have signed my name to this specification.

DWIGHT F. KILGOUR.
